[57] CLAIM

The ornamental design for a bird-like statuette or the like, as shown and described.

DESCRIPTION

FIG. 1 is a left side elevational view of a bird-like statuette or the like showing my new design.

FIG. 2 is a bottom plan view thereof.

FIG. 3 is a perspective view thereof.

The opposite side is substantially a mirror image of the side shown, with the exception of the head which is cocked toward the left.
